VANITY CASE

August Mitchell, New York, N. Y., assignor to
Scovill Manufacturing Company, Waterbury,
Conn., a corporation of Connecticut

Application May 23, 1935, Serial No. 22,934

7 Claims. (Cl. 132—82)

This invention relates to vanity cases.

It is an object of the invention to provide an improved vanity case particularly suitable for loose powder and rouge and one that is simple 5 in construction and economical to manufacture.

With these general objects and others in view, the invention consists in the features, details of construction and arrangements of parts which will first be described in connection with the accompanying drawing and then more particularly pointed out.

In the drawing:

Fig. 1 is a perspective view of a vanity case constructed in accordance with the invention, 15 showing the lid open and the slide closed;

Fig. 2 is a plan view of the same with parts broken away and in section, showing the lid open and the slide partly open;

Fig. 3 is a sectional view (enlarged) taken on the line 3—3 of Fig. 1, with parts in elevation; and

Fig. 4 is a fragmentary plan view of one of the parts.

Referring to the drawing, the invention in its entirety includes an open-topped casing and means for dividing the same into two compartments, one for loose powder and the other for rouge or the like. While the two compartments may be partitioned off in various ways, in the embodiment here illustrated as an example, fitting in the rear portion of casing 11 is a housing 12, the front wall 13 of which serves as a partition. This partition divides the casing into an open-topped front compartment 14 for a rouge pad or the like (not shown) and a rear compartment 15, enclosed by the housing, for loose powder (not shown).

In carrying out the invention to what is now considered the best advantage, the housing 12 is in the form of a separate fitment that is retained 40 in position by the mere act of assembly. To this end, the side wall of the housing, except at the front, is formed to fit the contour of the corresponding parts of the casing wall. As will be apparent from the drawing, the irregular shape of 45 these walls retains the housing against any sliding movement in the casing. On the inner side of the casing wall are one or more nibs 16 which take into suitable holes in the housing wall. With the construction described, the separate fitment 50 forming housing 12 snaps into position and is frictionally retained therein with the use of an extraneous fastening device.

The housing 12 is conveniently formed in two telescoping parts, as appears more clearly in 55 Fig. 3. The lower part comprises a bottom and

an upstanding wall and the upper part comprises a cover and a depending wall. As the bottom part telescopes into the upper part, and as the latter is frictionally held in place as described, no fastening means is necessary between the two parts 5 of the housing.

The top wall or cover of housing 12 is dished slightly, as at 17, to form a powder well and space for an applicator pad or puff and has an opening 18 for discharge of or access to the powder. 10

The invention in its entirety includes a removable closure for the powder opening and this may conveniently take the form of a slide. In the embodiment here shown as an example, slidable in the upper part of compartment 15 just below its 15 cover, is a flat plate forming a closure slide 19. To this end, slide 19 has a T-head terminating in oppositely disposed lugs 20. These lugs slide on the upper edge of the lower part of the two-part housing, the rear end of the slide operating 20 in a slot 21 formed by cutting away the rear end walls of the two parts of the housing. The slide is guided laterally by the engagement of lugs 20 with false side walls 22 formed in the upper part of the housing. Movement of the slide 25 forward is limited by engagement of the end of the slide with the front wall of the housing and movement rearwardly is limited by the engagement of lugs 20 or the T-head with the 30 inward bends of the housing side wall (Fig. 2).

The invention in its entirety includes a lid for the casing and means whereby the closure slide is prevented from opening movement except while the lid is open. This may conveniently be accomplished by hinging the lid to the slide. To 35 this end, as here shown as an example, the lid 23 is in the form of a flat plate which seats on the upper edge of the casing side wall. The rear end of this lid is hingedly connected with the rear end of the slide by means hereinafter described. The lid is normally held closed by an eye 24 which takes over a pin 24a on the front end of the casing.

When the lid is closed and latched, closure slide 45 19 is necessarily in advanced position to cover or close powder opening 18 and is held in such position as long as the lid remains closed. Thus, any discharge of powder is prevented while the case is not in use. When the lid is opened, the slide is 50 free to move and the lid serves as a handle for pulling out the slide to uncover opening 18.

The invention in its entirety includes an overlay for one or more sides of the case, formed of a metal distinctive in color and appearance from 55

the metal of the case and in constructions embodying the invention to what is now considered the best advantage such overlay may be used to effect the hinge connection between the lid and 5 the closure slide.

In the embodiment here illustrated as an example, the lid 23 of the case is formed of nickel or chromium plated metal and the inner face may serve as a mirror. The front and rear edges of 10 the lid are cut away (Fig. 4) to form long, shallow notches 25. On the upper or outer face of the lid is overlaid a strip 26 of distinctive metal, e. g. a low brass, stamped into any desired decorative design, and held in place by having its ends bent 15 down into notches 25, as at 27 (Fig. 2). The drawing shows an overlay on the lid only but it is to be understood that a similar overlay may be applied to the bottom of the casing.

In the embodiment of the invention here illustrated as an example, the rear end of overlay strip 26 has a tongue rolled up to form a hinge knuckle 28 which is straddled by two similar knuckles 29 formed on the end of closure slide 19 to receive a hinge pintle 30. The front end of 25 the strip 26 has a tongue rolled up to form a knuckle 31 for latching eye 24.

If desired, the rouge compartment may have a simple hinged cover and there may be a layer of felt under the closure slide at the back wall 30 of the casing to prevent leakage of powder.

What is claimed is:

1. In a vanity case, and in combination, a housing for loose powder having an opening in the top thereof, a slide movable in the housing to cover and uncover said opening, the housing having a depression around said opening capacitated to receive a powder applicator, and a lid for the housing hingedly connected with said slide and movable away from and toward said housing with a 35 right line movement as the slide moves.

2. In a vanity case, and in combination, a casing having an open top, a partition dividing the casing into two compartments adapted to hold, respectively, loose powder and a rouge pad, a 45 cover for the loose powder compartment, said cover having an opening therein, a slide movable to cover and uncover said opening, and a lid for said casing hingedly connected with said slide and movable away from and toward said casing 50 with a right line movement as the slide moves.

3. In a vanity case, and in combination, a casing having an open top, a housing seated in said casing and having an area less than that of the casing, whereby the housing encloses a compartment for loose powder and serves as a partition forming, with part of the casing, a second compartment for a rouge pad or the like, the top wall 55 of said housing having an opening therein, a slide

movable in said housing to cover and uncover said opening, and a lid for said casing hingedly connected with said slide and movable away from and toward said casing with a right line movement as the slide moves.

4. In a vanity case, and in combination, a housing for loose powder having an opening in the top thereof, a slide movable in the housing to cover and uncover said opening, the housing having a depression around said opening capacitated to receive a powder applicator, a lid for the housing, a separate strip secured to said lid and formed of a metal distinct in color and appearance from the metal of the lid, said strip and said slide having respective hinge knuckles, and a pintle passing through said knuckles to hingedly connect the lid with the slide.

5. In a vanity case, and in combination a box-like casing, a substantially flat plate forming a lid for said casing, a strip of metal overlaid on 20 said plate and having its ends turned down over the ends thereof thereby to be secured thereto, the rear end of said strip having a tongue rolled up to form a hinge knuckle, a complementary hinge knuckle carried by said casing, and a hinge 25 pintle in said knuckles.

6. In a vanity case, and in combination, a box-like casing, a substantially flat plate forming a lid for said casing, a strip of metal overlaid on 30 said plate and having its ends turned down over the ends thereof thereby to be secured thereto, a hinge connection between said casing and said lid, the forward end of said strip having a tongue rolled up to form a knuckle, a latching eye suspended in said knuckle, and a latching pin on said 35 casing for receiving said eye.

7. In a vanity case, and in combination, a casing having an open top, a two-part housing shorter than the casing and fitting in one end thereof, whereby the housing encloses a compartment for loose powder and partitions off a second compartment for a rouge pad or the like, one of said housing parts comprising a bottom and an upstanding side wall and the other part comprising a top and a depending side wall telescoping over said upstanding side wall, the housing top having an opening therein, a slide movable in said housing to cover and uncover said opening, a lid for said casing hingedly connected with said slide and movable away from and toward said casing with a right line movement as the slide moves, and oppositely disposed lugs on the inner end of the slide slidable on the upper edge of said upstanding side wall as the slide moves, the housing having a portion to be engaged by said lugs to limit outward movement of said slide.

AUGUST MITCHELL.
